UNITED STATES PATENT OFFICE.

HAROLD DUNCAN GRINNELL, OF PITTSFIELD, MASSACHUSETTS.

ELECTRIC GAS-LIGHTER.

1,032,203.

Specification of Letters Patent.

Patented July 9, 1912.

Application filed July 20, 1911. Serial No. 639,643.

To all whom it may concern:

Be it known that I, HAROLD D. GRINNELL, a citizen of the United States, and a resident of Pittsfield, in the county of Berkshire and State of Massachusetts, have invented a new and Improved Electric Gas-Lighter, of which the following is a full, clear, and exact description.

The invention relates to electric gas lighters, such as shown and described in the application for Letters Patent of the United States, No. 596,048, filed by me on December 7, 1910.

The object of the present invention is to provide a new and improved electric gas lighter having spark terminals for convenient and quick attachment to the gas burner tip without requiring any constructive changes in the tip, at the same time directing the jump spark across the burner opening to ignite the gas, and to prevent the spark terminals from being unduly heated by the gas flame of the burner. For the purpose mentioned use is made of caps for attachment to the arms of an acetylene gas burner or other burner, the caps having sparking points extending toward each other and terminating at opposite sides of a gas outlet opening, so that a jump spark passing from one point to the other ignites the gas issuing through the said outlet opening.

A practical embodiment of the invention is represented in the accompanying drawings forming a part of this specification, in which similar characters of reference indicate corresponding parts in all the views.

Figure 1 is a sectional side elevation of the improved electric gas lighter as applied to an acetylene gas burner, the section being on the line 1—1 of Fig. 2; Fig. 2 is a plan view of the same; and Figs. 3 and 4 are plan views of the blanks for forming the terminal caps.

The burner tube A carrying the acetylene gas or other gas burner tip B extends through an opening C' formed in the bottom C² of a lamp casing C, and the said burner tube A is provided with a flange A' resting on the upper surface of the bottom C². On top of the flange A' is seated a base D, of a suitable insulating material, and the said base is fastened in position by bolts E engaging the bottom C² of the lamp casing C. The base D is provided with a

central opening D' through which extends the burner tube A.

Binding posts F are held on the base D and are connected by wires G with a source of electrical energy, and the said binding posts F are provided with transversely-extending arms F' supporting hooks F² engaged by the lower ends of resilient members H, preferably in the form of coil springs hooked at their upper ends onto hooks I² of spark caps I and I' attached to the upper ends of the angular arms of the burner tip B. Each of the spark caps I and I' is preferably made from a single piece of sheet metal (meteor metal or other heat-resisting metal) and the strip of sheet metal is cut to form an end plate I³ from which extends the hook I², and on opposite sides of the end plate I³ are arranged apertured lugs I⁴, I⁵, and spark points I⁶ extend from the end plate I³ directly opposite the hooks I², as will be readily understood by reference to Figs. 3 and 4. The end plate I³ fits onto the end of the corresponding angular arm of the burner tip B, and the hooks I² are bent at right angles to the end plate I³ and against the underside of the burner tip arm so as to receive the end of the corresponding resilient member H. The apertured lugs I⁴ and I⁵ are likewise bent at a right angle to the end plate I³, so as to overlie the front and rear faces of the corresponding arm of the tip B, and the openings in the lugs I⁴, I⁵ register with the air holes leading to burner tip gas outlets B', so as not to obstruct the free flow of the air to the outlets B'. The spark points I⁶ for the caps I and I' are of different length, that is, as shown in the drawings, the spark point I⁶ for the cap I' is very short and terminates adjacent the gas outlet opening of the right-hand arm of the tip B on which the cap I' is fitted. The spark point I⁶ of the spark cap I is sufficiently long to extend down the left-hand arm of the tip B and up the right-hand arm, to terminate adjacent the gas outlet opening B' opposite the short spark point I⁶ of the cap I'. The long spark point I⁶ is provided with an opening I⁷ registering with the gas outlet opening on the left-hand arm of the tip B, so as to permit a free escape of gas through the said outlet opening B' and the opening I⁷. By forming caps in the manner described they can

readily be placed in position on the ends of the arms of the burner tip B, and by having the resilient members H connected with the hooks I², it is evident that the said resilient members H serve to hold the caps firmly in position, as the pull exerted by the resilient members is in a downward direction. It will also be noticed that the caps I and I' can be removed from the ends of the tip arms without disconnecting the resilient members H from the caps.

It is understood that when the electric gas lighter is used a jump spark passes from one spark point I⁶ to the other across the opening B' on the left-hand arm of the tip B so that the gas escaping through the said opening is ignited and thus it ignites the gas issuing from the gas outlet B' on the other arm of the tip B.

It will be noticed that the caps I and I' fit very snugly on the arms of the burner tip B, and hence do not come in direct contact with the flame of the burner, and consequently the caps are not unduly heated by the flame.

Having thus described my invention, I claim as new and desire to secure by Letters Patent:

1. In an electric gas lighter, a plurality of caps adapted to be mounted on the arms of a burner tip and having integral spark points extending toward each other and adapted to overlie the burner tip arms, the points being spaced apart at a gas outlet opening of the burner tip, the said caps also

having integral hooks, and resilient members of conducting material and connected with the said hooks to hold the caps in position on the burner tip arms, the said resilient members having elasticity sufficient to permit of disconnecting the caps from the burner tip arms.

2. In an electric gas lighter, a pair of caps adapted to be freely disposed on the burner tip and having integral spark points extending toward each other and spaced apart at the gas outlet opening of the burner tip and resilient members engaging portions of said caps to hold the same in position.

3. In an electric gas lighter, a pair of caps adapted to be freely disposed on a burner tip, said caps being formed of sheet metal bent to provide end plates for engagement with the end of the burner tip, and apertured lugs for engagement with the front and rear sides of the tip at the air supply holes, and spark points extending to one of the gas outlet openings of the tip, said caps being further provided with depending hooks, and resilient conductors engaging the said hooks for maintaining the caps in position.

In testimony whereof I have signed my name to this specification in the presence of two subscribing witnesses.

HAROLD DUNCAN GRINNELL.
